UNITED STATES PATENT OFFICE.

WILLIAM E. SCUTCHALL, OF HOPEWELL, PENNSYLVANIA, ASSIGNOR OF ONE-THIRD TO JAMES G. COLES AND ONE-THIRD TO CHARLES H. RIGHNOUR, BOTH OF HOPEWELL, PENNSYLVANIA.

ELECTRIC TRAIN CONTROL.

Application filed January 25, 1923, Serial No. 614,876. Renewed November 17, 1926.

This invention relates to certain new and useful improvements in electric train controls for steam locomotives wherein electric train control devices associated with a steam locomotive are operable independently of the usual air-brake mechanism that is under the control of the engineer so that the air brakes may be applied in case of danger should the engineer fail to observe danger signals.

10 The primary object of the invention is to provide an electric train control for steam locomotives wherein electrically operated devices rendered operative by energized track ramps are employed for shutting off the 15 steam supply from the steam chest of the locomotive to the slide valve cylinder and operate entirely independently of the air brake control in the engineer's cab, the shutting off of the steam supply to the slide valve cylinder simultaneously automatically opening a by-pass in the air brake line for applying the brakes, the electric train control being rendered operative for applying the air brakes should the engineer fail to observe 25 danger signals.

With the above and other objects in view as the nature of the invention is better understood, the same consists of the novel form, combination and arrangement of parts hereinafter more fully described, shown in the accompanying drawings and claimed.

In the drawings, wherein like reference characters designate corresponding parts throughout the several views.

35 Figure 1 is a fragmentary side elevational view of the conventional type of steam locomotive equipped with the electric train control for applying the air brakes independently of the air brake applying mechanism under control of the engineer.

40 Figure 2 is a fragmentary front elevational view of the locomotive showing the electric train control mechanism at each side thereof and associated with each drive cylinder,

45 Figure 3 is a vertical longitudinal sectional view of the drive and slide valve cylinders showing the electric control cylinder interposed in the steam line or pipe extending from the steam chest of the locomotive to the slide valve cylinder, the manipulating

cylinder associated with the electric control cylinder and the solenoid for operating a valve to by-pass the steam through the manipulating cylinder,

55 Figure 4 is a diagrammatic front elevational view showing the brushes for contacting the track ramp and wire connections to the switches at each side of the locomotive for operating the solenoids,

60 Figure 5 is a fragmentary detail view showing a ramp engaging contact roller used in lieu of the brushes illustrated in Figs. 2 and 4, and

65 Figure 6 is a top plan view of a portion of a track showing the intermediate ramp rails, the semaphore signal, and the electric wire connections and switch for energizing the ramp rails.

Briefly described, the present invention 70 aims to provide an electric train control for steam locomotives that will be rendered operative for applying the air brakes of the train, should the engineer fail to observe danger signals, the electric train control devices operating entirely independently of the manual control of the engineer, the devices being operated through the medium of contact members carried by the locomotive engaging energized track ramps to close an 80 electric circuit for shutting off the steam supply from the steam chest of the locomotive to the slide valve cylinder and simultaneously releasing air for the automatic application of the air brakes, release thereof 85 requiring the engineer to leave his cab and operate certain devices at each side of the locomotive for releasing the air brakes, throwing the electric train control apparatus to a set position, the latter operating to prevent head-on or rear end collisions in a manner to be hereinafter specifically described.

90 The type of electric train control disclosed in this application is readily adapted for steam locomotives of the usual construction, and embodies what is hereinafter referred to as an "electric control cylinder" interposed in the steam pipe connection between the steam chest of the locomotive and the slide valve cylinder, and further, what is herein 95 after referred to as "a manipulating cylinder," the electric control and manipulat-

- ing cylinders being alined and each having a piston working therein connected by a single rod. A solenoid shifted by contact members carried by the locomotive engaging track ramps directs steam into either end of the manipulating cylinder for reciprocating the piston therein, the piston in the electric control cylinder being shifted thereby for shutting off the passage of steam from the 5 electric control cylinder to the slide valve cylinder, movement of the piston in the electric control cylinder opening the air line for the brakes and applying the same. The electric train control devices are so located as to 10 require the engineer to leave the cab for releasing the same, and the air brakes, and, as above stated, operates entirely independently 15 of the engineer's control of the slide valve cylinder and air brakes.
- 20 Referring more in detail to the accompanying drawings, and particularly to Figs. 1, 2, and 6, the electric train control is associated with a steam locomotive of the usual type embodying a boiler body 10 mounted 25 in the ordinary manner upon a truck that carries drive wheels 11, the boiler body 10 being further supported by the saddle 12 as shown in Fig. 2, while the drive wheels 11 are illustrated as engaging the usual track 30 rails 13. As shown in Figs. 1 and 2, the boiler body 10 has associated with each side thereof adjacent the front end, a slide valve cylinder 14 and a drive cylinder 15 disposed therebeneath and suitably supported on the 35 saddle 12 and boiler body 10 in the usual manner and covered by a casing member 16 as clearly shown in Fig. 1.
- Devices constituting the electric train control for the locomotive are associated with 40 each slide valve cylinder at opposite sides of the boiler body 10, and embodies an electric control cylinder 17 disposed above the slide valve cylinder, preferably at the inclination illustrated in Fig. 2, the electric control cylinder 17 being housed by the casing member 16 as shown in Fig. 1. The means for establishing communication between the boiler body 10 and the electric control cylinder 17 includes an interiorly positioned 45 steam pipe 18, illustrated by dotted lines in Fig. 2 that extends from the steam chest of the boiler body to the exterior steam pipe casting 19 that communicates with the port 20 in the upper side of the electric control cylinder as shown in Fig. 3. The drive 50 and slide valve cylinders are of usual construction, the former having the piston 21 reciprocating therein, and through the medium of the piston rod 22 communicating motion to the drive wheels 11. The spacing 55 wall 23 between the drive and slide valve cylinders has end ports 24 that are controlled by the slide valve 25 in the slide valve cylinder, while communication between 60 the electric control cylinder and the slide

valve cylinder is had through the port 26 formed in the spacing wall 27 between said cylinders.

The electric train control further includes a manipulating cylinder 28 supported by 70 a bracket 29 carried by the boiler body 10 as shown in Figs. 1 and 2, and is positioned forwardly of and longitudinally alined with the electric control cylinder 17. A rod 30 is slidable through bushings 31 75 carried by the adjacent end of the electric control and manipulating cylinders, the forward end wall of the cylinder 17 carrying an inwardly directed relatively long bearing 32, the opposite ends of the rod 30 carrying pistons 33 and 33^a working respectively in the electric control and manipulating cylinder.

The air brake mechanism for the train includes a compressed air tank 34, preferably 80 supported on the boiler body 10 as shown in Fig. 1, an air pipe 35 extending from the rear end of the tank 34 leading to a position in the cab of the locomotive to be controlled by the engineer, the pipe 35 having a check valve 36 therein to prevent backflow of air pressure and extending to the three-way valve casing 37 having a single outlet pipe 38 in direct communication with the brake shoes. The air brake pipe line 90 that is operated by the electric train control mechanism is entirely independent of the pipe line 35 under control of the engineer, and includes, as shown in Figs. 1 and 3, a pipe section 39 extending from the forward 100 end of the compressed air tank 34 to the upper side of and entering the electric control cylinder 17 with a manually operable valve 40 carried thereby. The rear end of the electric control cylinder has a pipe line 105 41 tapped therein, the pipe 41 being provided with a check valve 42 and continuing for attachment to the three-way valve casing 37 to discharge through the single outlet pipe line 38, air passage through the rear end of the electric control cylinder being normally shut off by the piston 33 positioned adjacent the rear end as illustrated in Fig. 3.

The steam pipe connections extending between the manipulating cylinder 28 and the exterior steam pipe casting 19 are disposed beneath the boiler body 10 between the cylinders and the saddle 12 as shown in Fig. 2 and includes a vertically disposed pipe section 43 extending from the steam pipe 19 with a forwardly directed section 44 coupled to the lower end thereof, the horizontal sections 44 carrying an upwardly directed intermediately positioned branch pipe 45 having a manually operable valve 46 therein while the upper end of the branch extension 45 communicates with the rear end of the manipulating cylinder 28 at the inner side thereof as indicated at 47. The forward 115 120 125 130

end of the horizontal pipe section 44 carries an upwardly directed branch extension 48 having a manually operable valve 49 therein with the upper end of the branch extension 48 entering the lower side of the forward end of the manipulating cylinder 28 as at 50. The front and rear ends of the manipulating cylinder 28 carry pet cocks 51 and 52 respectively for purposes presently to appear. The control devices for diverting or feeding steam from the steam pipe 19 to the manipulating cylinder 28 includes a box 53 supporting exteriorly thereof a lever 54 to the free end of which one end 15 of a link rod 55 is connected, the other end of the link rod 55 being connected to the lever 56 that controls the valve 57 in the vertical pipe section 43.

The box 53 is supported by a bracket 58 mounted upon the saddle 12 as clearly shown in Figs. 1 and 2, the box 53 containing a solenoid 59 that has a pin connection 60 with the bearing shaft of the lever 54, as clearly shown in Fig. 3. The electric wiring system and track structure consists in laying the track rails 13 in block sections insulated as at 61, shown in Fig. 6, with a pair of ramp rails 62 supported on the ties 63 between the track rails 13 adjacent the forward end of each block. The wire connections between the contacts and switch blades carried by the boxes 53 and the ramp rails 62 are shown more clearly in Figs. 1 and 4, a contact brush 64 engaging one 35 of the ramp rails 62 has a wire connection 65 with the terminal —a— carried by one of the boxes, a wire 66 connected as at 67 to the line wire 65 leads to the terminal —a'— carried by the box 53 at the other 40 side of the body. The contact brush 64' engaging the other ramp rail has a line wire connection 65' with the terminal —b— of the adjacent box, the wire 66' connected as at 67' to the wire 65' extending to the terminal —b'— of the other box 53, each of the contacts carried by the boxes being provided with a switch blade 68. Wire connections 68^a extend from the terminals —a— and —a'— to the respective switch 45 blade 68, while wire connections 68^b extend from the terminals —b— and —b'— to the respective switch contacts 53^a. The brushes 64 are supported in any convenient manner upon the forward truck frame of the locomotive as illustrated in Fig. 1, and if desired, contact members 64^a of the type illustrated in Fig. 5 may be employed in lieu of the contact brushes, the contact member 64^a having a tensioned roller 69 that engages 50 the ramp rail 62.

The electrical devices for energizing the spaced ramps 62, as illustrated in Fig. 6, includes a battery 70 having a lead wire 71 extending from one pole thereof to one 55 of the ramps 62, the lead wire 72 from the

other pole of the battery 70 being connected to a contact 73 housed within a signal post 74 having a semaphore arm 75 pivotally mounted at the upper end thereof. A link rod 76 disposed within the post 74 is connected to the semaphore arm 75 to be shifted thereby, the lower end of the link rod carrying a contact 77 to which one end of a line wire 78 is connected, the other end of said wire extending to the other ramp 75 62, the ramps 62 being energized when the semaphore arm 75 is lowered to its horizontal danger position as illustrated in Fig. 6 by closing engagement of the contacts 73 and 77. 80

In the operation of the semaphore and the energizing of the ramps 62, the track rails 13 engaged by the drive wheels 11 in a block cause, in the usual manner by electrical apparatus, the lowering to a danger 85 position of the semaphore arm 75 in the proper rearwardly disposed block, the lowering of the semaphore arm closing the contacts 73 and 77 for energizing the ramp rails 62 that are engaged by the contact brushes 64 and 64' for bridging the circuit and transmitting power to the switches carried by the boxes 53 for operating the solenoids 59 under control of the switch blade 68 on a train approaching from the rear. The train control mechanism directly associated with the slide valve cylinder 14 has the pistons 33 and 33^a in the electric control and manipulating cylinders 17 and 28 respectively normally positioned at the rear ends of said 90 cylinders as illustrated in Fig. 3, the piston 33 closing the air line pipe 39, the valve 40 of which is normally open, the piston 33 being disposed rearwardly of the port 20 in the electric control cylinder to permit a 95 free flow of steam from the steam chest in the boiler body 10 into the electric control cylinder, and through the port 26 in the block 27 into the slide valve cylinder, and thereafter discharged into the drive cylinder 100 105 110 115 120 125 130 135 140 145 150 155 160 165 170 175 180 185 190 195 200 205 210 215 220 225 230 235 240 245 10000 10005 10010 10015 10020 10025 10030 10035 10040 10045 10050 10055 10060 10065 10070 10075 10080 10085 10090 10095 10100 10105 10110 10115 10120 10125 10130 10135 10140 10145 10150 10155 10160 10165 10170 10175 101

end of the manipulating cylinder sliding the piston 33^a forwardly therein with air escaping through the pet cock 51, the forward movement of the piston 33^a carrying the piston 33 forwardly in the electric control cylinder 17, movement thereof being limited by the piston 33 engaging the relatively long bearing 32 for opening the air line pipe 39 and closing the port 20 in the side of the electric control cylinder, steam confined within the forward end of the cylinder 17 escaping by way of the cutaway portion 27^a in the separating block 27 between the electric control and slide valve cylinder. The supply of steam to the slide valve cylinder is shut off by the piston 33 and the flow of compressed air from the tank 34 through the rear end of the electric control cylinder, as will at once be evident from an inspection of Fig. 3 is permitted, the air traveling through the pipe 41, through the three-way valve 37 and single outlet pipe 39 for the application of the brakes. It will therefore be seen that the electric train control operates entirely independently of the steam and air brake control that is operated by the engineer, so that in case the engineer should fail to observe danger signals, the energized ramp rails 62 electrically associated with the solenoids 59 immediately release the steam through the by-pass pipe sections above described for shutting off the steam supply to the slide valve cylinder and automatically opening the air brake line for applying the brakes. In resetting the apparatus, and releasing the air brakes, it is necessary that the engineer leave his cab for operating such devices, such as closing the pet cock 51 and opening the pet cock 52, closing the valve 46 in the branch pipe 45 and opening the valve 49 in the branch pipe 48, permitting steam from the pipe 19 to flow into the forward end of the manipulating cylinder 28 for forcing the pistons 33^a and 33 rearwardly in their respective cylinders for establishing communication between the steam pipe 19 and the slide valve cylinder, and also for shutting off the air brake pipe line 39 as shown in Fig. 3, steam in the rear end of the manipulating cylinder 28 escaping through the pet cock 52, the releasing of the electric train control devices being further accomplished by the switch blades 68 being thrown to open positions, see Figs. 2 and 4, for breaking the current between switch blades 68 and contacts 53^a, when the contact brushes engage the energized ramp rails 62, it being understood that after the contact brushes are moved out of engagement with the energized ramp rails 62, the switch blades 68 may again be moved into engagement with the contacts 53^a. As above stated, the electric train control apparatus operates entirely independently of the locomotive control in charge of the engi-

neer, the same when being set to an operative position being automatically operated when energized ramp rails 62 are engaged by contact members, the apparatus simultaneously shutting off the supply of steam to the slide valve cylinder and opening the air brake line for applying the brakes. The separating of the contacts 73 and 77 in the signal post 74 is accomplished when a train leaves the block that operated for lowering the semaphore arm to danger position, the semaphore arm being elevated and through the link rod connection 76 with the contact 77, separating said contacts. When the semaphore arm is in a vertical position indicating a clear track ahead, the line wires extending from the battery 70 to the ramp rails 62 are dead, and contact brushes 64 and 64' passing in engagement with the ramp rails will not be affected thereby as the semaphore arm 75 shifted by a train in a certain block energizes ramp rails 62 in a rearwardly positioned block that may represent any desired block in the track.

While the present embodiments as herein illustrated are what are believed to be preferable for accomplishing the purpose intended, it is to be understood that various changes are contemplated as will fall within the scope of the subject matter claimed.

What is claimed as new is:—

1. In an electric train control for locomotives, the combination with the slide valve cylinder, of electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

2. In an electric train control for locomotives, the combination with the slide valve cylinder, of manually releasable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

3. In an electric train control for locomotives, the combination with the slide valve cylinder and compressed air tank for the air brakes, of electrically operated de-

5 vices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders and means for admitting steam to 10 the manipulating cylinder for moving the piston in the electric control cylinder for shutting off the supply of steam to the slide valve cylinder.

15 4. In an electric train control for locomotives, the combination with the slide valve cylinder and compressed air tank for the air brakes, of manually releasable electrically operated devices for simultaneously shutting off the supply of steam to the slide valve cylinder and opening the air brake line, said electrically operated devices including an electric control cylinder interposed in the source of steam supply to the 20 slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

25 5. In an electric train control for locomotives, the combination with the slide valve cylinder having means under control of the engineer for feeding steam thereto, of independently operable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

30 6. In an electric train control for locomotives, the combination with the slide valve cylinder having means under control of the engineer for feeding steam thereto, of independently operable manually releasable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

for shutting off the supply of steam to the slide valve cylinder.

7. In an electric train control for locomotives, the combination with the slide valve cylinder and compressed air tank for the air brakes, of independently operable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

8. In an electric train control for locomotives, the combination with the slide valve cylinder and compressed air tank for the air brakes, of independently operable and manually releasable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders and means for admitting steam to the manipulating cylinder for moving the piston in the electric control cylinder for shutting off the supply of steam to the slide valve cylinder.

9. In an electric train control for locomotives, the combination with the slide valve cylinder and compressed air tank for the air brakes, and wherein devices are operable by the engineer for supplying steam to the slide valve cylinder and opening the air brake line, of independently operable electrically operated devices for shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, and means for admitting steam to the manipulating cylinder for moving the piston in the electric control cylinder for shutting off the supply of steam to the slide valve cylinder.

10. In an electric train control for locomotives, the combination with the slide valve cylinder and compressed air tank for the air brakes, and wherein devices are operable by the engineer for supplying steam to the slide

valve cylinder and opening the air brake line, of independently operable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, and means for admitting steam to the manipulating cylinder for moving the piston in the electric control cylinder for shutting off the supply of steam to the slide valve cylinder.

11. In an electric train control for locomotives, the combination with the slide valve cylinder, of electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

12. In an electric train control for locomotives, the combination with the slide valve cylinder, of manually releasable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to

be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

13. In an electric train control for locomotives, the combination with the slide valve cylinder and compressed air tank for the air brakes, of electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

14. In an electric train control for locomotives, the combination with the slide valve cylinder and compressed air tank for the air brakes, of manually releasable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to

valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

15. In an electric train control for locomotives, the combination with the slide valve cylinder having means under control of the engineer for feeding steam thereto, of independently operable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

45. 16. In an electric train control for locomotives, the combination with the slide valve cylinder having means under control of the engineer for feeding steam thereto, of independently operable manually releasable electrically operated devices for shutting off the supply of steam thereto, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to be

opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

17. In an electric train control for locomotives, the combination with the slide valve cylinder and compressed air tank for the air brakes, of independently operable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

18. In an electric train control for locomotives, the combination with the slide valve cylinder and compressed air tank for the air brakes, of independently operable and manually releasable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control and manipulating cylinders, means for admitting steam to the manipulating cylinder for moving the piston in the electric control cylinder for shutting off the supply of steam to the slide valve cylinder, the air brake line being associated with one end of the electric control cylinder and normally closed when steam

is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

19. In an electric train control for locomotives, the combination with the slide valve cylinder and compressed air tank for the air brakes, and wherein devices are operable by the engineer for supplying steam to the slide valve cylinder and opening the air 15 brake line, of independently operable electrically operated devices for shutting off the supply of steam to the slide valve cylinder and opening the air brake line, said electrically operated devices including an electric 20 control cylinder interposed in the source of steam supply to the slide valve cylinder, a manipulating cylinder associated with the electric control cylinder, connected pistons in the electric control and manipulating 25 cylinders, means for admitting steam to the manipulating cylinder for moving the piston in the electric control cylinder for shutting off the supply of steam to the slide valve cylinder, the air brake line being associated 30 with one end of the electric control cylinder and normally closed when steam is flowing into the slide valve cylinder and adapted to be opened when the piston is moved to shut off the supply of steam to the slide valve cylinder, said electrically operated devices further including a switch box associated 35 with each electric control and manipulating cylinder, a solenoid enclosed therein, the means for admitting steam to the manipulating cylinder including a pipe line, a valve therein, operative connections between said valve and solenoid, and energizable track ramps electrically connected to the solenoid.

20. In an electric train control for locomotives, the combination with the slide valve cylinder and compressed air tank for the air 40 brakes, and wherein devices are operable by the engineer for supplying steam to the slide valve cylinder and opening the air brake line, of independently operable electrically operated devices for simultaneously shutting off the supply of steam to the slide valve cylinder and opening the air brake line, said electrically operated devices including an electric control cylinder interposed in the source of steam supply to the slide valve cylinder, a manipulating cylinder associated with the electric control cylinder, connected pistons in the electric control 45 and manipulating cylinder, means for admit-

ting steam to the manipulating cylinder for moving the piston in the electric control cylinder for shutting off the supply of steam to the slide valve cylinder, the air brake line being associated with one end of the electric 70 control cylinder and normally closed when steam is flowing to the slide valve cylinder and adapted to be opened when the piston is moved to shut off the supply of steam to the slide valve cylinder, said electrically operated devices further including a switch box associated with each electric control and manipulating cylinder, a solenoid enclosed 75 therein, the means for admitting steam to the manipulating cylinder including a pipe line, a valve therein, operative connections between said valve and solenoid, and energizable track ramps electrically connected to the solenoid.

21. In an electric train control for steam 80 locomotives, the combination with the slide valve cylinder at each side thereof, of an electric control cylinder interposed in the source of steam supply to each slide valve cylinder, compressed air tanks for the air 85 brakes, throttle control means for delivering air from the tank to the brakes, an air line extending from each tank to the adjacent control cylinder and from the cylinders to the brakes, and electrically operated means for shutting off the supply of steam to the slide valve cylinders and opening the air 90 lines to apply the brakes.

22. In an electric train control for steam locomotives, the combination with the slide 100 valve cylinder at each side thereof, of an electric control cylinder interposed in the source of steam supply to each slide valve cylinder, compressed air tanks for the air 105 brakes, throttle control means for delivering air from the tanks to the brakes, an air line extending from each tank to the adjacent control cylinder and from the cylinders to the brakes, a manipulating cylinder aligned with each control cylinder, pistons in the control 110 and manipulating cylinders, a single rod connecting the same, and electrically operated means associated with the manipulating cylinders for shifting the pistons for shutting off the supply of steam to the slide 115 valve cylinder and opening the air lines to apply the brakes.

23. In an electric train control for steam locomotives, the combination with the slide 120 valve cylinder at each side thereof, of an electric control cylinder interposed in the source of steam supply to each slide valve cylinder, compressed air tanks for the air 125 brakes, throttle control means for delivering air from the tanks to the brakes, an air line extending from each tank to the adjacent control cylinder and from the cylinders to the brakes, a manipulating cylinder aligned with each control cylinder, pistons in the control 130 and manipulating cylinders, a single rod

connecting the same, pipe connections between the source of steam supply and the manipulating cylinders, and electrically operated means for admitting steam to the 5 manipulating cylinders for shifting the two pistons for simultaneously shutting off the supply of steam to the slide valve cylinders and opening the air lines to apply the brakes.

24. In an electric train control for steam locomotives, the combination with the slide valve cylinder at each side thereof, of an electric control cylinder interposed in the source of steam supply to each slide valve cylinder, compressed air tanks for the air 10 brakes, throttle control means for delivering air from the tanks to the brakes, an air line extending from each tank to the adjacent control cylinder and from the cylinders to the brakes, a manipulating cylinder alined 15 with each control cylinder, pistons in the control and manipulating cylinders, a single rod connecting the same, pipe connections between the source of steam supply and the manipulating cylinders, main supply valves 20 in the pipe connections, a solenoid operatively connected to each valve and track ramps electrically connected to the solenoids for energizing the same to open the valves for admitting steam to the manipulating cylinders for shifting the two pistons for simultaneously shutting off the supply of steam to the slide valve cylinders and opening the air lines to apply the brakes, a switch box 25 inclosing each solenoid and switch levers for deenergizing the solenoids.

26. In an electric train control for steam locomotives, the combination with the slide valve cylinder at each side thereof, of an electric control cylinder interposed in the source of steam supply to each slide valve cylinder, compressed air tanks for the air brakes, throttle control means for delivering air from the tanks to the brakes, an air line extending from each tank to the adjacent control cylinder and from the cylinders to the brakes, a manipulating cylinder alined 30 with each control cylinder, pistons in the control and manipulating cylinders, a single rod connecting the same, pipe connections between the source of steam supply and the manipulating cylinders, main supply valves 35 in the pipe connections, a solenoid operatively connected to each valve, track ramps electrically connected to the solenoids for energizing the same to open the valves for admitting steam to the manipulating cylinders for shifting the two pistons for simultaneously shutting off the supply of steam to the slide valve cylinders and opening the air lines to apply the brakes.

25. In an electric train control for steam locomotives, the combination with the slide valve cylinder at each side thereof, of an electric control cylinder interposed in the source of steam supply to each slide valve cylinder, compressed air tanks for the air 40 brakes, throttle control means for delivering air from the tanks to the brakes, an air line extending from each tank to the adjacent control cylinder and from the cylinders to the brakes, a manipulating cylinder alined with each control cylinder, pistons in the control and manipulating cylinders, a single rod connecting the same, pipe connections 45 between the source of steam supply and the manipulating cylinders, main supply valves in the pipe connections, a solenoid operatively connected to each valve, track ramps electrically connected to the solenoid for energizing the same to open the valves for admitting steam to the manipulating cylinders for shifting the two pistons for simultaneously shutting off the supply of steam to the slide valve cylinders and opening the air lines to apply the brakes, a switch box inclosing each solenoid, switch levers for deenergizing the solenoids, the pipe connections including branch pipes entering each end of the manipulating cylinders and manually operable valves in the branch pipes.

In testimony whereof I affix my signature.

WILLIAM E. SCUTCHALL.
